UNITED STATES PATENT OFFICE

ALFRED L. KRONQUEST, OF SYRACUSE, NEW YORK, ASSIGNOR TO CONTINENTAL CAN COMPANY, INC., OF NEW YORK, N. Y., A CORPORATION OF NEW YORK

SEAMING HEAD FOR CLOSING MACHINES

Application filed April 28, 1931. Serial No. 533,560.

The invention relates to new and useful improvements in a seaming head for closing machines, and more particularly to a seaming head which is rotated during the seaming operation.

An object of the invention is to provide a seaming head of the above type wherein the seaming rolls are carried by arms mounted on relatively long actuating spindles which travel with the rotating head and which are capable of yielding for permitting the seaming rolls to cross the side seam during the seaming of the end to the can body.

A further object of the invention is to provide a seaming head of the above type wherein the arms which carry the seaming rolls have associated therewith means for shifting the set positions of the arms relative to the spindle.

20 A still further object of the invention is to provide a seaming head of the above type wherein the seaming rolls are held on the arms through interengagement of the rolls with the chuck, and wherein the cam follower which actuates the spindles is capable of being moved to and from operative position for permitting the swinging of the arm so as to disengage the roll from the chuck so that it can be detached from the arm.

25 These and other objects will in part be obvious and will in part be hereinafter more fully disclosed.

In the drawings which show by way of illustration one embodiment of the invention—

30 Figure 1 is a side view of a seaming head embodying the improvements;

Fig. 2 is a plan view of the head detached from its supporting shaft and with one of the top plates removed;

Fig. 3 is a sectional view through the head on the line 3—3 of Fig. 2 of the drawings;

Fig. 4 is a sectional view on the line 4—4 of Fig. 3;

Fig. 5 is a vertical sectional view on the line 5—5 of Fig. 2;

Fig. 6 is a view at the upper end of the seaming head with the operating cam in section and showing the upper spindle arms and followers associated therewith in plan,

the followers being in operative position, and

Fig. 7 is a similar view but showing the followers as swung to inoperative position.

The invention is directed to a seaming head which includes a rotating head portion on which are mounted a plurality of vertically disposed spindles. Each spindle is provided with an arm carrying a seaming roll. As shown, there is an arm rigidly attached to the spindle, and a companion arm which carries the seaming roll which is freely mounted on the spindle. The two arms are connected by a worm sector and a worm gear which may be utilized for shifting the arm carrying the seaming roll to different set positions on the spindle. The spindle is oscillated for bringing the seaming roll into contact with the metal parts for forming the seam, by a cam follower cooperating with a reciprocating cam which rotates with the head. This cam follower is attached to an arm fixed to the upper end of the spindle. It is so connected to the arm that it may be shifted to an inoperative position, that is, moved away from contact with the cam. The seaming roll is held on the arm with which it is associated by a chuck with which said seaming roll has continuous interengagement. When the follower is moved to inoperative position, the spindle may be turned so as to disengage the seaming roll from the chuck and this permits the seaming roll to be detached from its supporting arm.

Referring more in detail to the drawings, the seaming head includes a rotating head portion 1 which is attached to a flanged head 2 carried by a sleeve 3. This sleeve 3 is rotated continuously, and through the flanged head imparts rotation to the head portion 1. Located centrally of the head portion 1 is a chuck 4. Said chuck is carried by a sleeve 5, and between the sleeve 5 and the rotating head portion 1 are ball bearings 6 and 7. The sleeve carrying the chuck is splined to a center rod 8 which carries a stripper pad 9. This center rod 8 is held from rotation, and this will hold the chuck from rotation. The chuck and the can on which the seaming head is operating remains

stationary. The supporting bracket located beneath the seaming head on which the end is placed, is indicated at 10 in the drawings. Said bracket has a seat for the end and also 5 a tapered opening 11 which engages the can body, rounding up the same, and centering the can body so that the end will be seated therein. The stripping pad 9 cooperates with the support for the can in bringing 10 about the seating of the end in the can, and also the stripping of the can from the chuck after the seam has been formed.

The seaming head, as shown in the drawings, is provided with four spindles, each of 15 which is vertically disposed, so that the axis of the spindle is substantially parallel with the axis of the rotating head. These spindles are indicated at 12 in the drawings. They are all similar, and a description of one will 20 answer for the others. Each spindle carries, at the lower end thereof, an arm 13. The arm 13 has a sleeve hub which fits a substantially rectangular portion 14 at the lower end of the spindle. Thus it is that the arm 13 is 25 firmly locked to the spindle so that there can be no axial movement of the arm on the spindle. Directly beneath this arm 13 is another arm 15 which carries the seaming roll 16. The arm 15 is mounted for free movement angularly on the spindle 12. Said arm has a hub portion which engages the cylindrical lower end of the spindle, and is held thereon by means of a locking bolt 17 bearing against a washer 18. The arm 13 which is rigidly secured to the spindle 12 is provided with a 30 segment gear 19. Mounted on the arm 15 is a worm shaft 20 which engages the segment gear 19. The worm shaft 20 is clamped against a seat at the inner end thereof, by a locking bolt 22. When the bolt 22 is released, the worm shaft can be turned, shifting the arms relative to each other, and then the bolts set up, locking the arms in their set position. The seaming roll is mounted on a roller bearing 23, which in turn is mounted on a cylindrical stud 24 formed integral with the arm 15. The roller bearing and seaming roll are slipped on to this cylindrical stud, after 35 which the spindle is shifted so as to cause the groove 25 in the seaming roll to engage a rib 26 on the chuck 4, and this interengagement of the seaming roll and chuck is what holds the seaming roll on the cylindrical stud 24.

At the upper end of the spindle 12 is an 40 arm 27 which is rigidly attached to the spindle 12, preferably being formed integral therewith. This arm 27 carries a cam follower 28. The cam follower 28 is mounted on a bushing carried by a cylindrical stud 29 which is attached to the arm 27. The arm 27 has swinging movement imparted thereto through this follower. A plate 30 attached to the head serves as a wear plate, and holds the cam follower on the cylindrical 45 stud 29. This cam follower is provided with

a V-shaped nose 31 which cooperates with a cam 32 attached to a sleeve 33, which sleeve rotates with the seaming head and has endwise movement relative to the sleeve 3 carrying the seaming head. The cam 32 is provided with a projecting cam face 34 at the right thereof as viewed in Fig. 3, and with a cam face 35 at the left thereof, as viewed in this figure. The cam face 34 operates on the follower associated with the spindle carrying 50 the first-operation seaming roll, while the cam face 35 operates on the follower associated with the second-operation seaming roll. There are two first-operation rolls and two second-operation rolls. They are diametrically disposed relative to each other. On the first part of the downward movement of the cam 32, the first-operation seam rolls are 55 active, after which they are withdrawn, and then the second-operation seaming rolls are rendered effective. When the cam 32 is at the extreme lower end of its stroke, there is a cutaway portion 34a just above the cam face 34, and a cut-away portion 35a just above the cam face 35, which are brought opposite the 60 respective followers, cooperating with these cam faces 34 and 35. The same is true of the other followers and the cams controlled thereby. When in this position, a cam follower may turn on its supporting spindle to the full 65 line position in Fig. 7. When the cam followers have been turned to this position, then the spindle carrying the seaming rolls can be turned so as to disengage the seaming rolls 70 from the chuck. When the seaming rolls, or any one of them, are disengaged from the chuck, they may be moved endwise on their supporting spindles, and detached from the supporting arms carrying the same. 75

The spindles carrying the seaming rolls are 80 of sufficient length so that said spindles will yield to permit the seaming roll to cross the side seam, and at the same time, the seaming roll is held firmly in contact with the metal parts so as to insure a tight rolled seam at 85 both sides of the side seam. When it is desired to adjust the position of any one of the seaming rolls relative to the spindle, this can be readily accomplished through the worm shaft adjustment provided therefor. When 90 the worm shaft is turned, it will cause through its engagement with the segment worm gear, a shifting of the arm, and consequently a shifting of the seaming roll relative to its supporting and actuating spindle. 95 When it is desired to remove the seaming roll for any purpose, this can be readily done by turning the cam follower to an inoperative position so that the spindle can be swung to 100 disengage the roll from the chuck. When 105 the roll has been replaced on the arm supporting the same, the spindle is swung to cause said seaming roll to engage the chuck, and then the cam follower is returned to its 110 operative position. It will be noted that the 115 120 125 130

swinging of the cam follower back into its operative position restores the parts to their original setting. In other words, the connection between the seaming roll and the actuating cam has been released, and the shifting of the parts permitted for the removing of the roll, and when the roll is replaced, the parts may be at once returned to their original setting. No adjustment of the rolls as to timing is necessary when a roll is removed and another substituted therefor.

It is obvious that minor changes in the details of construction and the arrangement of the parts may be made without departing from the spirit of the invention as set forth in the appended claims.

Having thus described the invention, what I claim as new and desire to secure by Letters-Patent, is—

20 1. A seaming head for can closing machines comprising a rotating head portion, a stationary chuck associated therewith, a plurality of vertically disposed spindles carried by said head portion, an arm attached to the lower end of each spindle, a seaming roll carried thereby, an arm attached to the upper end of said spindle, a cam follower mounted thereon, a reciprocating cam rotating with said head and operating on said cam followers, said seaming rolls being held on the supporting arms therefor by interengagement with the chuck, and means whereby the cam follower may be moved to inoperative position to permit the spindle to be shifted so as 35 to disengage the seaming roll from the chuck, whereby the seaming roll may be detached from its supporting arm.

2. A seaming head for can closing machines comprising a rotating head portion, a stationary chuck associated therewith, a plurality of spindles carried by the head portion and extending in a direction parallel with the axis of rotation of the head, an arm attached to the lower end of each spindle, a seaming roll carried thereby, an arm attached to the upper end of each spindle, a cam follower mounted thereon, a reciprocating cam mounted on said head and engaging said cam followers, said seaming rolls being held on the supporting arms therefor by interengagement with the chuck, and means whereby the cam followers may be turned on their respective arms so as to clear the operating cam therefor and permit the spindle to be shifted so as to disengage the seaming roll from the chuck.

3. A seaming head for can closing machines comprising a rotating head portion, a stationary chuck associated therewith, a plurality of spindles carried by the head portion and extending in a direction parallel with the axis of rotation of the head, an arm attached to the lower end of each spindle, a seaming roll carried thereby, an arm attached to the upper end of each spindle, a

cam follower mounted thereon, a movable cam mounted on said head and engaging said cam followers, said seaming rolls being held on the supporting arms therefor by inter-engagement with the chuck, and means whereby the cam followers may be shifted on their respective arms so as to clear the operating cams therefor and permit the spindle to be shifted so as to disengage the seaming roll from the chuck.

In testimony whereof, I affix my signature.

ALFRED L. KRONQUEST.
